In France May 22, 1945

6 Claims. (Cl. 263—30)

1

The present invention relates to transverse circulation shaft furnaces, that is to say furnaces in which the matters to be treated are, in the course of their downward movement through the shaft, subjected to the action of a stream of hot gases flowing transversely thereto.

It is known that transverse circulation of the heating gases has for its effect to avoid the dependence that exists, in shaft furnaces of the so-called "counter-current" category, between the value of the section afforded for the passage of the solid material and that of the section afforded for the passage of the gaseous stream.

But, in counterpart to this advantage, transverse circulation involves a specific inability to utilize as fully as with a counter-current circulation, the heat of the gaseous stream and therefore requires a greater volume of heating gases for obtaining the same effect.

In practice, this specific inability is further accentuated by the fact that the factors of operation of the furnace, to wit the flow rate of the gaseous stream, the length of its travel through the solid mass, the size of the solid fragments and the length of time for which they are heated should be chosen by taking into account certain relations that must exist between them.

If these relations are not complied with, the unitary production capacity of the shaft furnace and the rate of utilization of the heat supplied by the gases are reduced to a degree which may be very important.

The chief object of the present invention is to eliminate these drawbacks and to improve the furnaces of the kind in question in such manner as:

1. To increase the rate of utilization of the heat present in the gases and to give this rate a value practically equal to that obtained with counter-current circulation;

2. To permit of ensuring an accurate adaptation of the proportions to be observed between the various factors to be considered: flow rates of the solid and gaseous streams, length of the gaseous travel, size of the solid fragments, duration of the heating of the solid mass, whatever be the capacity of production of the furnace;

3. To increase, to an important degree, the capacity of production per unit of volume of the shaft;

4. To permit the treatment of solid materials reduced into very small fragments.

The principle of my invention consists chiefly in subdividing the shaft into a plurality of superposed sections and causing the stream of hot gases admitted into the lower section, to pass

2

after having flown transversely through said section, into the section located immediately above it, to flow therethrough in the same transverse direction and so on up to the outlet of the uppermost section so that the gaseous stream can gradually give off its heat to the solid mass by flowing therethrough several times, in the same transverse direction, at higher and higher levels.

Another feature of my invention which is preferably to be utilized simultaneously with that above set forth but can be utilized independently, consists in subdividing the shaft vertically into several juxtaposed elements through which distinct streams of hot gases flow transversely, the width of each element and, consequently, the thickness of the layer of solid materials through which the gaseous streams must flow being judiciously determined as a function of the size of the solid fragments that are treated and/or of the gaseous flow rate so that the pressure drop in each gaseous stream remains below a given limit.

Preferred embodiments of my invention will be hereinafter described with reference to the accompanying drawings, given merely by way of example and in which:

Figs. 1 and 2 show, in diagrammatic vertical section, two shaft furnaces of the transverse circulation type made according to two different embodiments of the invention, respectively.

In the example shown by Fig. 1, the metallic wall 1 of the shaft is given the shape of a quadrangular vertical prism, of rectangular or square-shaped section, with a feed orifice 2 at the top, and a conical outlet 3 at the bottom. In the furnace is provided a vertical passage 4 limited, across the whole width of the shaft, by two perforated walls or grids 5¹ and 5², and through which the fragments of matter to be treated move downwardly.

According to my invention, the furnace is divided into several superposed sections for instance two sections which correspond substantially, but not necessarily, each to one half of the height of the shaft. The separation between these two sections is materialized by a constricted portion or neck 6 provided in passage 4 at this place and by a limitation in the upward direction of the zone of admission of the hot gaseous stream. This stream enters the bottom part of the shaft through at least one orifice 7 of adjustable section opening into the space between the lateral left wall of shaft 1 and perforated wall 5¹. The limitation of the admission zone is ensured by a solid horizontal partition 9¹ which divides said space into two chambers 8 and 11 having no direct communication between them.

The space between perforated partition 5² and the right hand wall of the shaft is divided into two compartments 10^a and 10^b by a partition 9² analogous to 9¹ and a conduit 20 leads from compartment 10^a to interval 11.

The hot gas stream, admitted at 7, therefore passes through the holes of partition 5¹, flows through the solid matters that are present in the lower half of passage 4, enters compartment 10^a, and flows upwardly through this compartment. The gases collected in the upper portion of compartment 10^a are led to chamber 11 through conduit 20 and flow, in the same transverse direction as the first time, through the upper section of passage 4, into compartment 10^b while the outflow of the gases takes place through one or several orifices 12 provided at the top of compartment 10^b.

Owing to the path of travel followed by the stream of hot gases through the shaft, from its inflow to its outflow, in the course of which said stream is caused to flow twice, in the same transverse direction and in different respective thermic conditions, through the material to be treated, I ensure a heating of this material which is analogous to the methodical heating obtained in a shaft furnace with counter-current circulation.

This constitutes an important advantage with respect to the kind of heating that takes place in known transverse circulation shaft furnaces. In these furnaces, the heat of the gases is utilized but in an incomplete manner due to the fact that, as the temperature of the solid material rises more and more as the material is moving down through the shaft, said material becomes less and less capable of absorbing the heat supplied by the gaseous stream passing transversely through the shaft with a uniform flow rate over its whole height. It follows that, while the temperature of the gases that leave the furnace is, at the top, little different from the temperature of the solid materials that have just entered the shaft, it rises gradually toward the bottom of the shaft where it becomes equal to the temperature of the gases entering the shaft. Consequently, the gaseous stream issues from the upper portion of the shaft at a mean temperature approximating that of the matters that have just entered the furnace and from the lower portion of the shaft at a mean temperature approximating its own inlet temperature. Thus, for instance, if the solid materials and the hot gases are introduced into the shaft at respective temperatures of 150° C. and 400° C., the mean temperature of the outflowing gases is 230° C.

On the contrary, if, according to the invention, the solid materials and the hot gases are admitted at 2 and at 7 at the same respective temperatures as above stated, the gaseous stream, after flowing successively through the lower half and the upper half of the shaft, has a mean temperature of 163° C. at outlet 12. The thermic balance of the furnace has, therefore, been considerably improved owing to a more efficient exploitation of the heat fed by the gaseous stream and to a more rational heating effect on a solid mass of smaller height and the particular temperature of which is such, when this mass is in contact with the gaseous stream, that it can more easily absorb the heat supplied by this stream.

In the example shown by Fig. 2, shaft 1 is divided in the transverse direction, into several elements, for instance four in number, respectively designated by A, B, C and D. Elements A and B or C and D are separated from each

other by an intermediate wall including a solid middle partition 13 and two perforated lateral partitions 14¹ and 14² so as to form passages 16¹, 16², 16³ and 16⁴ through which gaseous streams can circulate.

The distance between a lateral wall of the shaft and an adjacent intermediate wall or between two adjacent intermediate walls, that is to say the width of passages A, B, C, D is judiciously calculated with a view to improving the rate of utilization of the heat of the gases and to permitting the treatment of solid fragments of very reduced dimensions which, up to now, could hardly be treated in furnaces of this kind.

It is known that the coefficient of heat transmission between a gas and a solid is in direct ratio to the flow rate of the gaseous stream and in inverse ratio to the dimensions of the solid fragments. Therefore, the specific resistance opposed by the solid mass to the circulation of the gaseous stream is proportional to the coefficient of heat transmission. In order to increase this coefficient of transmission without involving an excessive pressure drop in the gaseous stream, the spacing of the vertical partitions and consequently the number of elements of the shaft, are chosen as a function of the gaseous flow rate and of the size of the solid particles treated in the furnace, so that the pressure drop in the gaseous stream does not exceed a fixed value.

Owing to the increase of velocity of the gaseous flux, which results from the fact that the gas must flow through a smaller thickness of solid materials, and to the possibility of treating materials constituted by finer particles, I obtain an increase of the heat transmission coefficient which corresponds to a considerable improvement of the unitary treatment capacity of the shaft as illustrated by the following example:

In a given case where the relations to be observed between the various factors above mentioned imposed a height of the shaft equal to ten times its width, it has been possible to reduce its necessary height to 1.25 times this width by subdividing the shaft, in the transverse direction, into four elements and the unitary treatment capacity has been brought to eight times what it was initially.

In the example shown by Fig. 2, I have used not only the last mentioned feature, but also the feature above described with reference to Fig. 1, according to which the shaft is divided into two distinct sections superposed to each other and through which the same portion of the total gaseous stream flows successively. However, this combination is not necessary in all cases and it may be sufficient to divide the shaft, over its whole height, into a single series of juxtaposed distinct elements.

In the example shown by Fig. 2, the gaseous streams are introduced through orifices 7¹, 7² and 7³ into the lower compartments 8¹, 8² and 8³. These distinct streams flow separately in the transverse direction through the solid masses present in the passages 15¹, 15², 15³ and 15⁴ of the lower half of the shaft and enter chambers 16¹, 16², 16³ and 16⁴. From these chambers, the gases pass, through conduits 20¹, 20², 20³, 20⁴ into chambers 11¹, 11², 11³ and thence through the solid masses present in the passages 17¹, 17², 17³ and 17⁴ of the upper half of the shaft, toward upper chambers 21¹, 21², 21³ and 21⁴ provided with outlet orifices 12¹, 12², 12³ and 12⁴. It should be noted that compartments 8² and 11² are

separated from each other by an auxiliary partition 18⁵, chamber 16¹ is separated from chamber 21¹ by a partition 18¹ and so on.

This transverse circulation shaft furnace complies well with the conditions above set forth and is well adapted to the thermic treatment of any solid material in fragments or particles of any degree of granulometry, and, in particular, much finer than could be treated up to now in furnaces of this kind. Furthermore, the thermic and unitary output of such a furnace are much better due to the rational circulation that is adopted for the gaseous stream with a view to bringing it into contact with the fragmentary or granular material.

It should be well understood that my invention is in no way limited to the embodiments above described, which have been given merely by way of example.

What I claim is:

1. A shaft furnace which comprises, in combination, a vertical shaft, at least two transverse vertical perforated partitions in said shaft extending each from one side thereof to the opposite side so as to form between them a passage for the solid material to be treated, with two distinct chambers left on opposite sides of said passage respectively for the flow of the gaseous stream used for heating this material, two partitions transverse to the vertical direction extending each between one of said perforated partitions and the adjacent shaft wall so as to divide each of said chambers into two superposed compartments, the lower compartment of one chamber being provided with a gas inlet, and a conduit outside of said passage, connecting the lower compartment of the other chamber with the upper compartment of the first chamber, the upper compartment of the second mentioned chamber being provided with a gas outlet.

2. A shaft furnace which comprises, in combination, a vertical shaft, at least two transverse vertical perforated partitions in said shaft extending each from one side thereof to the opposite side so as to form between them a passage for the solid material to be treated, with two distinct chambers left on opposite sides of said passage respectively for the flow of the gaseous stream used for heating this material, two partitions transverse to the vertical direction extending each between one of said perforated partitions and the adjacent shaft wall so as to divide each of said chambers into two superposed compartments, the lower compartment of one chamber being provided with a gas inlet, a conduit outside of said passage, connecting the lower compartment of the other chamber with the upper compartment of the first mentioned chamber, the upper compartment of the second mentioned chamber being provided with a gas outlet and means for restricting the horizontal section of said passage substantially at the level of said partitions transverse to the vertical direction.

3. A shaft furnace which comprises, in combination, a vertical shaft, at least two transverse vertical perforated partitions in said shaft extending each from one side thereof to the opposite side so as to form between them a passage for the solid material to be treated, with two distinct chambers left on opposite sides of said passage respectively for the flow of the gaseous stream used for heating this material, and at least one pair of horizontal partitions extending each between one of said perforated partitions and the adjacent shaft wall so as to divide each

of said chambers into at least two superposed compartments, the lower compartment of one chamber being provided with a gas inlet, a conduit outside of said passage, connecting the lower compartment of the other chamber with the upper compartment of the first mentioned chamber, the upper compartment of the second mentioned chamber being provided with a gas outlet.

4. A shaft furnace which comprises, in combination, a vertical shaft, at least two transverse vertical perforated partitions in said shaft extending each from one side thereof to the opposite side so as to form between them a passage for the solid material to be treated, with distinct chambers left on either side of said passage for the flow of the gaseous stream used for heating this material, at least one pair of horizontal partitions extending each between one of said perforated partitions and the adjacent shaft wall so as to divide each of said chambers into at least two superposed compartments, the lower compartment of one chamber being provided with a gas inlet, a conduit outside of said passage, connecting the lower compartment of the other chamber and the upper compartment of the first mentioned chamber, the upper compartment of the second mentioned chamber being provided with a gas outlet, and means for restricting the horizontal section of said passage substantially at the level of said horizontal partitions.
5. A shaft furnace which comprises, in combination, a vertical shaft, at least two transverse vertical perforated partitions in said shaft extending each from one side thereof to the opposite side so as to form between two such partitions a vertical passage for the downward flow of the solid material to be treated and on either side of this passage a distinct chamber for the upward flow of the gas stream used for heating this material, at least one pair of horizontal partitions in said chambers, respectively, so as to divide each of said chambers into at least two superposed compartments, the lower compartment of one chamber being provided with a gas inlet, and a conduit outside of said vertical passage, connecting the lower compartment of the other chamber with the upper compartment of the first mentioned chamber, the upper compartment of the second mentioned chamber being provided with a gas outlet.
6. A shaft furnace which comprises, in combination, a vertical shaft, at least two transverse vertical perforated partitions in said shaft extending each from one side thereof to the opposite side so as to form between two such partitions a vertical passage for the downward flow of the solid material to be treated and on either side of this passage a distinct chamber for the upward flow of the gas stream used for heating this material, at least one pair of horizontal partitions in said chambers, respectively, so as to divide each of said chambers into at least two superposed compartments, the lower compartment of one chamber being provided with a gas inlet, a conduit outside of said vertical passage, connecting the lower compartment of the other chamber with the upper compartment of the first mentioned chamber, the upper compartment of the second mentioned chamber being provided with a gas outlet, and means for restricting the horizontal section of said passage substantially at the level of each pair of horizontal partitions.
